ADJUSTABLE SAFETY RAZOR

Filed Aug. 10, 1928

INVENTOR
E. W. ANDERSON

Carl H. Crawford
ATTORNEY

UNITED STATES PATENT OFFICE

EARL W. ANDERSON, OF SPOKANE, WASHINGTON

ADJUSTABLE SAFETY RAZOR

Application filed August 10, 1928. Serial No. 298,798.

The object of this invention is to provide a novel type of safety razor.

The invention involves a blade holder and a handle which are connected in a novel adjustable manner so that the blade holder can be adjusted from a shaving position into the plane of the handle.

It is a feature of the invention to provide means for operatively connecting the blade in the blade holder, with the handle, so that when the blade holder and handle are adjusted to various different positions, the blade will be actuated by such adjustment into various positions in the blade holder.

15 Thus, in the most specific form of the invention, it is a feature to provide means whereby on one character of relative adjustment of the blade holder and handle, the blade will occupy a shaving position, and on another character of adjustment, the blade will be retracted into the blade holder, and on still another adjustment, the blade will be projected from the blade holder.

It is a further feature to provide a blade holder, as set forth, which is readily opened or adjusted for quick removal of the blade when necessary and wherein the operative connection of the blade with the holder will be established automatically merely by the insertion of the blade into the holder.

The device of my invention also includes a novel form of blade which I claim as new, as an article of manufacture.

The invention has many other objects and features which will be more fully described in connection with the accompanying drawing and which will be more particularly pointed out in and by the appended claims.

In the drawing:

40 Fig. 1, is a view showing the blade holder adjusted from a shaving position into the plane of the handle with the blade in a shaving adjustment or position.

45 Fig. 2, is a view showing the blade holder adjusted into a position to retract the blade into the blade holder.

Fig. 3, is a view showing the blade holder adjusted into a position to project the blade from the blade holder.

50 Fig. 4, is an edge view showing the blade

holder in a shaving position with respect to the handle.

Fig. 5, is an enlarged sectional view on line 5—5 of Fig. 1, with the parts in the same position as shown in said figure.

55 Fig. 6, is a sectional view on line 6—6 of Fig. 2.

Fig. 7, is a sectional view on line 7—7 of Fig. 3.

Fig. 8, is a further enlarged sectional view 60 on line 8—8 of Fig. 5.

Fig. 9, is an enlarged view of the blade holder showing the same in an open position and illustrating the operative connection of the blade with certain mechanism of the 65 holder.

Fig. 10, is a face view of my improved blade.

Fig. 11, is an edge view thereof.

Like characters of reference designate similar parts throughout the different figures of the drawing.

Reference will first be made to Figs. 5 to 9 for the purpose of specifically describing the type of blade holding member or blade holder herein shown as embodying my invention.

Said blade holder includes what I will term a base or base plate 1 provided with blade receiving and holding means in the form of lateral flanges 2. The inner faces 3, of these flanges converge, as shown in Fig. 9, so that when a clamping device, to be presently described, is forced between said flanges, the latter will snap over and hold said device. The base plate has a face 4, which I will term the blade face, and an opposite face 5, which I will term the handle face. The shaving edge of the base plate is provided with the usual comb or guard composed of teeth 6, which may be formed integral with said plate.

I have provided a form of blade which is shown in Figs. 10 and 11, and which consists of a body 7, having a cutting edge 8, and provided with actuating means preferably in the form of a slot 9. This slot 9, as shown, is a linear slot that is not only parallel with the cutting edge but is disposed remote therefrom and relatively closer to the

55

70

75

85

90

95

100

base edge 10 than to the cutting edge 8. In accordance with my invention, this blade may be of the paper thickness so as to be cheap enough to be discarded, after a few usages, 5 or it may be of a thicker stock that will take repeated sharpening.

Now, reverting to Fig. 9, it will be seen that the blade 7, fits against the face 4 and between the flanges 2, the clearance between 10 the latter being sufficient for relative movement of the blade with respect to the blade holder.

Said blade holder includes blade clamping means which, in the form shown, is embodied 15 in a leaf 11 that is hinged at 12, to the rear ends 13, of flanges 2, so as to be swung into or out of clamping relation to the blade 7. As shown in Figs. 5 to 7, the leaf is closed and in Fig. 9, the same is open. The lateral edges 20 14, of said leaf 11, are parallel, and when forced between the converging edges 3, the leaf will snap into and be held in a blade clamping position. However, many other expedients may be devices to perform this 25 broad function and I do not wish to be limited to the form shown except for such limitations as the claims may import. I prefer to hinge the leaf 11, to the base plate 1, as in so doing, I am always sure that the free edge 30 15, of said leaf, will always be in predetermined relation with the guard, when said leaf is closed.

Reference will next be made to an operating member intermediate the handle and the 35 blade and which member is mounted in the blade holder.

Said member is shown in the form of a disc 16 which is peripherally shouldered at 17, in a complementally formed shouldered opening 40 in the base plate 1, so that said disc may be rotatively adjusted. This shouldered mounting, which is clearly shown in Figs. 5 to 7, prevents the disc from moving toward the blade, from its normal position and the 45 blade side or face of the disc 16 is flush with the blade face 4, of plate 1. On its blade side or face, said disc is provided with an operating pin 18, which is adapted to slidably engage slot 9, of blade 7. Said pin 18, is 50 preferably of sufficient length to extend past and through blade 7. I preferably provide leaf 11, with an arcuate guide slot 19 into which the free end of said pin 18 projects in order to assist in guiding said pin and to prevent any binding action during adjustment 55 of said disc.

Said disc 16, is of a thickness to dispose its remaining face substantially flush with what I will term the handle side of plate 1, as will 60 be seen from Figs. 5 to 7, and projecting from and mounted on said handle face are two journals 20. A handle member 21 has a reduced shank 22 that fits between said journals 20 and a suitably fixed pivot pin 23, pivotally 65 unites said handle with said disc. It will

now be seen that I have provided a connection between the blade holder and handle which comprises a combined swivel and pivotal connection, and that a part of this connection is operatively associated with the blade.

Before describing the operation, I will refer to a feature of the construction which not only functions to hold the disc in position but which additionally functions to hold the handle in different adjustive relation to 70 the blade holder.

A spring metal sheath retainer is indicated at 24, and that edge nearest the guard 6, is suitably secured to the handle face of the base plate 1, leaving the remaining edges 25, 26 and 27, free from engagement with said plate 1 and in suitable spaced relation thereto, as shown. Said sheath 24 has a slot presenting edges 28 and 29 and the edge 29 is so disposed with relation to journals 20, that in any relative position of the blade holder and handle, the sheath 24 will at least engage one of said journals and thereby retain the disc 16 in position, as shown.

In order to hold the blade holder in shaving relation to the handle, as shown in Fig. 4, I have provided means, which for the present illustration and purpose, may consist of a small link 30, suitably attached to the holder at 31, and to the handle at 32, and which attachments may be disconnected when the holder is to be adjusted into any of the positions shown in Figs. 1 to 3.

Thus it will be seen that the disc and handle may readily be detached from the blade holder by springing the sheath 24 sufficiently to release the disc 16 from the base plate 1. With such disconnection of the parts, it will be clear that with the blade holder opened, as shown in Fig. 9, the whole structure is 100 rendered accessible for cleaning or renewal purposes. In order to facilitate the holding of the handle and blade holder in the various relative positions shown, I consider it a feature of my invention to bend the corner portions 33 and 34, of the sheath 24, downwardly, as shown, so that the handle will be frictionally held in its various adjusted positions.

The razor as shown in the shaving position in Fig. 4, is no more compact for packing than any other safety razor of this type, either for gross shipment or for individual packing convenience. Furthermore, it is a feature of this invention to provide a safety razor with means for projecting a blade for 115 cleaning or stropping purposes and withdrawing or retracting the blade when the razor is not in use, thereby preventing exposure of the cutting edge. In the following description of the operation, I will explain 120 how and by what means the structure affords the above various advantages.

In the shaving position shown in Fig. 4, the edges 28 of the slot coat with the sides of the handle shank 22, to hold the blade holder 130

against rotary movement, and, combined with link 30, the holder will be rigidly retained. It will also be clear that in the Fig. 4, position, the disc 16 will hold the blade 7, in such relation to the guard 6, as to be in effective shaving relation thereto, such relation being shown in Fig. 5.

When it is desired to adjust the blade holder into the plane of the handle, the parts are adjusted into the position shown in Figs. 1 and 5, by disconnecting link 30 and shifting the blade holder as shown. This adjustment might, in itself, be a valuable and advantageous one apart from the adjustments to be presently described. However, the edge 8, of the blade 7, in this initial adjustment, is still in the same shaving position as in Fig. 4, and would of course not be protected. However, it will now be clear that the slot 20 in sheath 24 permits the holder to be adjusted from the shaving position shown in Fig. 4, to the initial collapsed position shown in Fig. 1.

Assuming that the user had finished shaving, in the course of this description, and wanted either to clean or strop the blade prior to putting it away, then, he would shift the blade holder into the position shown in Figs. 3 and 7, in which position the blade 30 is projected sufficiently to be cleaned of all lather or soap and is equally adapted to be stropped.

After the blade has been cleaned and stropped, then, the user can adjust the holder 35 into the position shown in Figs. 2 and 6, in which position the blade is retracted into the holder so as to be afforded the protection of the latter as a case therefor, the cutting edge being clearly out of a position for contact with anything.

Thus it will be seen that the user need never remove the blade either for cleaning or stropping purposes, and it will now be clear how the relative movement of the holder and handle serves, through the disc 16, and the pin and slot connection, to correspondingly shift the blade into the various positions shown.

It may be desirable to briefly recapitulate the operation in detail.

In shifting the holder and handle from the Fig. 1, to the Fig. 2, position, the disc 16 is positively actuated and by reason of the fact that the blade 7 is guided by the flanges 2, 55 I insure a positive and unvariable parallel relation between the guard 6 and the cutting edge 8, irrespective of the extent of movement of the blade 7. Further, by reason of the constant engagement of the pin 18 with slot 9, the blade 7 will be positively held in its adjusted positions.

When the holder and handle are relatively adjusted from the Fig. 2 to the Fig. 3, position, the disc 16 is actuated in the reverse direction to that illustrated in Fig. 2.

It is also informative to state that while the leaf 11 firmly engages the blade 7 and holds the latter sufficiently tightly against the base plate 1 to prevent wobbling movement of the blade, still, this engagement is not sufficient to burdensomely resist adjustment of the blade to the various positions shown and is only sufficient to act as an advantageous drag to prevent a too free movement of the holder and handle. Thus, in order to make the various adjustments shown in Figs. 2 and 3, it is not necessary to first release the leaf 11.

It is believed that the invention will be fully understood from the foregoing description, and while I have herein shown and described one specific form of my invention, I do not wish to be limited thereto except for such limitations as the claims may import.

I claim:

1. A safety razor comprising, a blade holder having a blade therein, a handle movably connected with said holder, and means operatively connected with said blade for automatically retracting said blade from a shaving position when said handle and holder are adjusted into one relative relation, or projecting the edge of said blade from said holder into a stropping position when said holder and handle are adjusted into another relative relation.

2. A safety razor comprising, a handle, a blade holder having a blade therein and said holder being tiltable from a shaving position into the plane of said handle and in T-shaped relation thereto, and means operatively connected with said blade for retracting said blade into said holder when said holder is shifted into one character of aligned relation to said handle, or projecting said blade from said holder when the latter is shifted into another character of aligned relation to said handle.

3. In a safety razor, a blade holder having a blade therein and a swivel disc operatively connected with said blade, and a handle pivoted to said disc for shifting said blade into different positions in said holder.

4. In a safety razor, a blade holder comprising a base plate and a leaf hinged thereto and said leaf having an arcuate slot therein, a blade adapted to be clamped between said plate and leaf and being provided with a linear slot, a swivel disc rotatable in said plate and having a pin projecting through said linear slot and into said arcuate slot, and a handle connected with said disc.

5. In a safety razor, a blade holder comprising a base plate having a blade and a handle face, a blade, a leaf connected with said plate to clamp said blade against said blade face, a swivel disc rotatable in said plate and extending through said blade face and being operatively connected with said

blade and extending thru said handle face, and a handle pivoted to said disc on the handle face of said plate.

6. In a safety razor, a handle, a blade holder tilttable on said handle from a shaving position into the plane of said handle and in T-shaped relation thereto, said holder being shiftable into different characters of alined relation to said handle, and a spring 10 retainer leaf on said holder having a slot permitting relative tilting movement of said holder and handle, said leaf extending laterally along said holder and engaging said handle when the latter is in different characters of adjustment to said holder.

15 In witness whereof, I have hereunto affixed my signature.

EARL W. ANDERSON.
